TYPE-WRITING MACHINE.

1,018,950.

Specification of Letters Patent.

Patented Feb. 27, 1912.

Application filed October 19, 1910. Serial No. 587,854.

To all whom it may concern:

Be it known that I, FRANK A. YOUNG, a citizen of the United States, residing in New York, in the county of New York and 5 State of New York, have invented certain new and useful Improvements in Type-Writing Machines, of which the following is a specification.

This invention relates to means for releasing platens from control by the line-space wheels of typewriting machines, and is in the nature of an improvement on the structure disclosed in U. S. Letters Patent No. 581,717, issued to G. W. Hall, May 4, 10 1897, in which the platen is releasable from the line-space wheel. Pressure against a sliding rod wedges the outer ends of a pair of toggle links against the line-space wheel to clutch the latter to the platen. An opposite movement of the rod releases the clutch.

The principal object of this invention is to simplify and improve the devices with a view to rendering the construction compact 25 and reliable, easily operated and inexpensive to manufacture.

In place of a toggle, I employ an axially 30 slideable head having a series of clutching dogs pivoted thereto, to grip the inner periphery of the drum of the line-space wheel and connect it to the platen.

Other features and advantages will hereinafter appear.

In the accompanying drawings, Figure 1 35 is a perspective rear view, showing the invention applied to an Underwood machine. Fig. 2 is a rear sectional elevation, the platen being clutched to the line space wheel. Fig. 3 shows the platen released. Fig. 4 is an end view, partly in section. 40 Fig. 5 is a perspective showing the parts disassembled and partly broken away.

Types 1 strike a platen 2 fast on an axle 3 journaled in the ends 4 of a platen frame. 45 A line-space wheel 5, having a drum 6, is loosely mounted on a barrel in the form of an annular flange 7 on a disk 8 fast to the axle, and is turned in the usual manner. The wheel is held against lateral displacement by a guard 9. The usual detent 10 engages the wheel.

The platen is clutched to the line-space wheel by three equidistant radially-extending dogs 14 hinged at 15 to a head or carrier 17 within the barrel 7; said dogs (of

which a greater or less number than three may be employed) projecting through slots 16 in the barrel to bite the inner periphery of the drum 6 of the line-space wheel. The dogs 14 fit snugly between the walls of the 60 slots 16, to prevent relative turning movement between the line-space wheel and platen when clutched together. They are pivoted in ears 18 projecting from the head 17, connected to rotate with, the platen. 65 These dogs 14 operate somewhat like toggles, the length of each dog being slightly greater than the distance between the inner periphery of the drum 6 and the pivot 15. The drum preferably has an interior annular groove 21, which may be substantially V-shaped in cross-section, in which the ends of the dogs 14 are confined, said dogs biting upon the opposite side walls of said groove to afford a powerful grip. A finger-piece 70 75 19 is provided upon the outer end of a sliding hollow plunger or stem 20, the latter connected to the head 17. When said plunger is pressed to the left at Fig. 2, it forces the head 17 to slide in axial direction to 80 rock the dogs and relieve the pressure of their outer ends upon the drum 6 to enable the platen 2 to be freely turned.

The inner end of the hollow plunger or stem 20 which is supported on the axle 3, is 85 cupped at 27 to slide over the hub 28 of the fixed disk 8. A returning spring 22 on the hub bears against the inner end of said plunger to return the head 17 to normal position, thereby causing the dogs 14 to bite the line-space wheel. The usual finger knob 23 to turn the platen 2 is fixed on a hub 24 which may encircle the plunger 20. Opposite set screws 25, passing through radial slots 26 in the plunger 24, and engaging a groove or depression 25^a in the axle, secure the knob 23 to the axle, and enable the knob to turn the axle and platen. Said screws 25 also operate to spline the plunger to the axle, and permit axial movement of the plunger to release the dogs. 90 95 100

By beveling the free ends of the dogs 14 (see Fig. 4) a comparatively slight pressure of the spring causes a strong bite. The strength of the bite is augmented by the sloping or converging sides of the groove, between which the dogs operate like wedges, causing great pressure and friction; the tips of the dogs being rounded or cut off so that they do not touch the bottom of the groove. 110

Also a rigid clutch connection may be obtained between the platen and line-space wheel by connecting the dogs with the barrel 7 at points adjacent the bite of the dogs 5 and wheel, as shown.

Having thus described my invention, I claim:

1. In a typewriting machine, the combination with a line-space wheel and a platen, 10 said wheel having a V-shaped groove, of a slotted barrel fast with the platen and on which the wheel is loosely mounted, and a clutch head within the barrel and having dogs projecting through slots in the barrel 15 to wedge between the walls of said V-shaped groove.

2. In a typewriting machine, the combination with a line-space wheel and a platen, said wheel having a V-shaped groove, of a 20 slotted barrel fast with the platen and on which the wheel is loosely mounted, a clutch head within the barrel and having dogs projecting through slots in the barrel to wedge between the walls of said V-shaped groove, 25 and a finger piece to control the head and dogs.

3. In a typewriting machine, the combination with a line-space wheel, and a platen and axle rotatable relatively thereto, of a 30 slotted barrel fast on the axle, a line-space wheel having a drum loosely mounted on the barrel, an axially slideable head, clutch dogs pivoted on the head and extending through the slots in the barrel, said drum having a 35 groove, the walls of which are engaged by the dogs, and a finger piece controlling the head.

4. In a typewriting machine, the combination with a line-space wheel having a V- 40 shaped groove, and a platen and axle rotatable relatively thereto, of an axially slideable head turning with the axle, and having radially extending ears, and dogs hinged between the ears and wedging into said V- 45 shaped groove.

5. In a typewriting machine, the combination with a line-space wheel, and a platen and axle adapted to turn relatively thereto, of an axially movable head having a slotted 50 plunger supported on the axle, a turning knob through which the plunger extends, a pin passing through the slot in the plunger to secure the knob to the axle and to spline the plunger to the axle, and a dog on the 55 head to bite the line-space wheel.

6. In a typewriting machine, the combination with a platen and axle, and a line-space wheel having a drum mounted loosely relatively thereto, and provided with a V-shaped 60 groove, of a spring-pressed head axially slideable within the drum and turning with the axle, radially-extending dogs pivoted on the head and of greater length than the distance between the inner periphery of the 65 drum and the pivotal points of said dogs, to

wedge in the groove of said drum, and a finger piece to control the head.

7. In a typewriting machine, the combination with a platen and its axle, of a line-space wheel having a grooved drum relatively to which the platen and axle are rotatable, an axially slideable head turning with the axle, dogs pivoted on the head, the free ends of the dogs accommodated in the groove to bite the drum, and a finger piece to release the dogs. 70

8. In a typewriting machine, the combination with a platen and axle, of a line-space wheel having a drum provided with a V-shaped groove, loosely mounted relatively 80 to the platen and axle, a dog connected to turn with the platen, the free end of the dog confined in said groove to wedge between the walls thereof to lock the platen and wheel together. 85

9. In a typewriting machine, the combination with a platen and axle, a barrel fixed thereto, and a line-spaced wheel loosely mounted on the barrel, of a clutch comprising an axially slideable head, dogs hinged to 90 the head to bite the line-spaced wheel, said dogs passing through axially-extending slots in the barrel to connect the clutch mechanism to the platen.

10. In a typewriting machine, the combination with a line-space wheel and a platen and axle rotatable relatively thereto, of a clutch mechanism to connect the platen and axle to the line-space wheel, a slotted hollow plunger supported on the axle and controlling the clutch mechanism, a finger knob having a hub through which the plunger extends, and a set screw passing through the slot in the plunger to connect the finger knob to the axle and spline the 100 plunger thereto. 100

11. In a typewriting machine, the combination with a platen, a platen axle and a line space wheel, of a releasable means for connecting the line space wheel to the platen, a finger piece to operate said releasing means, said finger piece having a hollow stem whereby it is mounted on said axle, a finger knob through which said hollow stem extends, said hollow stem provided with a longitudinal slot, and means passing through said slot to connect said finger knob to said axle. 110

12. In a typewriting machine, the combination with a platen, a platen axle and a line space wheel, of a releasable means for connecting the line space wheel to the platen, a finger piece to operate said releasing means, said finger piece having a hollow stem whereby it is mounted on said axle, a finger knob through which said hollow stem extends, said stem having between its ends a cutaway portion, and connecting means between said axle and said finger knob at said cutaway portion. 120 125 130

13. In a typewriting machine, the combination with a platen, a platen axle and a line space wheel, of a releasable means for connecting the line space wheel to the platen, 5 a finger piece to operate said releasing means, said finger piece having a hollow stem whereby it is mounted on said axle, a finger knob through which said hollow stem extends, and the said hollow stem provided with opposite longitudinal slots, and set 10 screws or devices passing through said slots to fasten said finger knob to said axle; the latter having a groove or depression to receive the points of the set screws.
